UNITED STATES PATENT OFFICE.

HARRY I. KILLION, OF WINTERSSET, IOWA.

METHOD AND APPARATUS FOR FORMING CONCRETE SUBSLEEPERS.

Application filed September 14, 1925. Serial No. 56,268.

This invention relates to the forming of suitable supports for wooden floors when used on top of a concrete floor.

It has heretofore been the practice to provide a series of parallel strips of wood which are laid on top of the concrete after it has hardened, and are usually secured in position by a number of metal strips or screed anchors. In actual practice the top surface of the concrete floor is usually more or less uneven and rough. It is, therefore, necessary to level the wooden strips or screeds by placing beneath them wooden wedges or other suitable supports, after which it is sometimes the practice to fill the space between the wedges with concrete by means of a trowel. This, however, is so slow and tedious that the filling of the space between the screeds and the floor is omitted which results in the screeds being supported upon the wedges alone, portions of the screeds sometimes resting directly on the high points of the concrete, which is sometimes covered with loose pebbles. This construction is objectionable due to the fact that the wedges have a tendency to work loose under constant use, and that portion of the screed which rests on the pebbles has a tendency to settle due to the fact that the pebbles are embedded in the screed due to the weight above.

It is, therefore, the object of my invention to provide a new and improved apparatus whereby the space between the screeds and the concrete floor may be easily and quickly filled with plastic concrete which will form a base for said screeds when hardened.

A further object is to provide a new method or process for laying the screeds and the concrete base, whereby the necessity of providing a large number of wedges will be eliminated and also whereby a more rigid and firm base may be easily, quickly and economically provided for said screeds.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a plan view of my improved apparatus for laying the concrete sub-sleepers.

Figure 2 is an end elevation of same.

Figure 3 is a transverse sectional view.

Figure 4 is a side elevation of one end of my improved device for forming concrete sub-sleepers.

Figure 5 is a side elevation showing the manner in which a screed is supported above the concrete base before the sub-sleepers are applied.

Figure 6 is a transverse sectional view of the concrete sleeper and the screed as mounted therein, as constructed by my improved method; and

Figure 7 is a detail sectional view taken on the line 7—7 of Figure 5.

In Figure 5 of the drawings I have used the reference numeral 10 to indicate the upper surface of the concrete floor which is shown in section in said figure, said concrete floor being poured in the usual manner, and while in a plastic condition a series of screed anchors 11 are inserted. Said anchors are arranged in rows, each of which is usually provided with a pair of upright members 12 spaced about two inches apart and are designed to have placed between them the screeds or wooden strips 13 which are usually about two inches square.

Due to the fact that the upper surface of the concrete base 10 is uneven, as clearly illustrated in Figure 5, it will be seen that if the screed 13 was laid directly on the top surface of the base 10, the upper edge of the screed would not fall in a common horizontal plane, due to the unevenness of the floor surface, and that the screed would be supported only at a number of points on the upper surface of the base, leaving the intermediate portions of the screed unsupported. To overcome this difficulty, it is necessary to wedge up the screeds so that the upper edges lie in a common horizontal plane, the wedges being provided to support the screed at any points where it does not touch the upper portion of the concrete floor. The screeds are then nailed or fastened to the anchors. Sometimes the space below the screeds is filled with concrete by means of a trowel, which is a very slow method. The under surface of the screed touches the floor at various points, thereby providing a very thin and narrow space, which, if it were possible to fill with concrete, would be very thin and crumbly, due to the fact that the concrete would dry too rapidly.

With my improved method I first ascertain the highest point in the floor surface and level the screeds from this point and support the screed at this point a considerable distance above the surface of the concrete floor, approximately one-half inch. I then level this screed and secure it rigidly in position with

the screed anchors 12 by means of nails 14, and then remove the wedges and use them for the next screed, which is leveled with the first one and secured in position in the same manner. After all of the screeds have been thus leveled and rigidly secured in position by this method, it will be seen that a space will be provided between the lower surface of all of the screeds and the said floor throughout the entire length of said screeds.

For forming the concrete base or sub-sleeper beneath the screeds, I have provided an apparatus which consists of a hopper having slanting side members 15 which terminate in downwardly extending portions 16 at their lower edges. The side members 15 are provided with end members 17. The downwardly extending members 16 are spaced apart six or eight inches. Extending longitudinally with the members 16 and between the end members 17 I have provided wall members 18 which are spaced apart a distance slightly greater than the width of the screeds 13. The lower edges of the members 18 are mounted considerably above the lower edges of the members 16, while the upper edges of the members 18 terminate in inwardly and upwardly extending portions 19 forming a wedge shaped cover with a space between the members 18. Each of the end members 17 is provided with a central slot 20 at its lower edge. The lower edge of said member 17 is provided with inclined edges 21. The outer surface of the members 16 are provided with axles 22, on which are mounted supporting wheels 23. The lower edges of the members 16 are supported slightly above the under surface of said wheels. The upper edges of the members 17 are provided with a longitudinally extending pipe 24 having outwardly extending portions to form handles by means of which the hopper may be lifted and moved from one screed to another. One end of the member 24 is preferably provided with an auxiliary handle 25, the handle portion of which extends transversely with the tube 24 and supported by means of brackets 26, the lower ends of which are bolted to the said pipe 24. This provides means whereby the hopper may be moved longitudinally with the screed. One of the end plates 17 is provided with a pair of trowel members 27 which are secured adjacent to and extended laterally from the inclined edges 21.

In practical use the hopper is lifted by the handles 24 and 25 and placed longitudinally with the screed so that the members 18 rest on each side thereof with the wheels 23 resting on the concrete floor. The hopper is then placed at one end of the screed with the trowels 27 adjacent to said end. The hopper is then filled with plastic concrete which is provided with enough water so the concrete will run quite freely. It will then be seen that the concrete will settle down between

the members 16 and 18 and onto the upper surface of the floor 10 and will run under the screed in the manner illustrated in Figure 3. The hopper may then be moved slowly and longitudinally with the screed which will permit the concrete to fill the entire space beneath the said screed, and a sub-base 28 will be formed similar to that illustrated in Figure 6, the cross section of which is the same shape as the lower edges 21 of the plates 17. The trowels 27 are so arranged that as the hopper is advanced, they will have a tendency to squeeze and crowd the plastic concrete into any spaces that are not filled by the pressure of the plastic concrete in the hopper, thereby providing means whereby a solid sub-sleeper will be provided. The lower edges of the members 18 are arranged at such a height that a considerable amount of the concrete will be filled against the outer edges of the screed, as clearly shown in Figure 6. This provides a brace for the screeds to prevent them from turning over. This also provides means whereby unevenness in the surface of the concrete floor may be taken care of, inasmuch as it will be seen that the hopper may be raised and lowered relative to the screed 13, in which case, of course, the inclined sides of the base 28 extend higher or lower on the screed and the thickness of the base beneath the screed will accordingly be varied. There will be, however, a sufficient amount of material extended against the side of the screed to prevent any turning tendency. The important feature is that the screed is supported on a firm sub-base of concrete which rests firmly on the concrete floor.

After the sub-base has been laid under one of the screeds, the hopper may then be lifted to another screed by means of the handles 24 and 25, and the operation repeated.

Thus it will be seen that I have provided an improved method whereby the screeds may be easily and quickly placed above a concrete floor and in proper alinement with each other, and which are supported on a concrete base in such a manner that they will not yield or squeak from continuous use after the floor has been laid, thereby providing a permanent and fixed anchor for the floor. It will further be seen that the concrete sub-base is at all points of sufficient thickness to cure properly to form a solid and firm mass.

It will further be seen that by my improved apparatus I have provided means whereby the concrete base may be quickly and easily and economically laid.

I claim as my invention:

1. A device for forming concrete sub-sleepers comprising a hopper provided with side and end members, the lower edges of said end members being inclined upwardly and inwardly and terminating in a vertical slot, a pair of wall members extending longitudi-

nally through said hopper and parallel with the said side members, and having their lower edges terminating with the lower end of said vertical slots, the upper edges of said inner wall members being inclined upwardly and inwardly to intersect each other, and supporting wheels for said hopper.

2. A device for forming concrete sub-sleepers comprising a hopper provided with side and end members, the lower edges of said end members being inclined upwardly and inwardly and terminating in a vertical slot, a pair of wall members extending longitudinally through said hopper and parallel with the said side members, and having their lower edges terminating in the lower end of said vertical slots, the upper edges of said inner wall members being inclined upwardly and inwardly to intersect each other, supporting wheels for said hopper, and a trowel member adjacent to each of the inclined edges of one of the end plates of said hopper.

3. A device for forming concrete sub-sleepers comprising a hopper provided with side and end members, the lower edges of said end members being inclined upwardly and inwardly and terminating in a vertical slot, a pair of wall members extending longitudinally through said hopper and parallel with the said side members, and having their lower edges terminating in the lower end of said vertical slots, the upper edges of said inner wall members being inclined upwardly and inwardly to intersect each other, supporting wheels for said hopper, and a trowel member adjacent to each of the inclined edges of one of the end plates of said hopper, and handles for lifting and carrying said hopper.

4. The method of forming a floor support which consists in first providing a plastic concrete floor and inserting therein while in a plastic condition a row of vertically arranged screed anchors, then permitting the concrete floor to harden, then providing a horizontal screed adjacent to said anchors, then temporarily supporting and leveling said screed so that its under surface is entirely above said concrete floor, then rigidly securing said screed to said anchors, then removing the temporary support and applying plastic concrete beneath said screeds in such a manner that the concrete will flow under the screeds by gravity, and then applying pressure to the upper surface of said plastic concrete so that the plastic concrete will be forced under said screed and the screed embedded partially therein.

5. An apparatus for forming concrete sub-sleepers comprising a hopper designed to con-

tain plastic concrete and to be advanced longitudinally over a screed spaced above a base, a shield device in the hopper shaped to overlap the top and sides of a screed and to prevent the flow of concrete from the hopper on top of the screed, said hopper being also formed with means whereby the flow of concrete from it will be directed downwardly and inwardly beneath the screed along which the hopper is being advanced.

6. The method of forming concrete sub-sleepers which consists in first providing a concrete base having a series of slender and upwardly projecting screed supporting members arranged in rows, then securing to the screed supporting members of each row a screed spaced above the base a slight distance, and then inserting a continuous concrete sub-sleeper in plastic condition between the base and said screed and around said screed supports.

7. The method of forming a floor support which consists in first providing a plastic concrete floor and inserting therein a row of vertically arranged screed anchors while the concrete is in a plastic condition, then permitting the concrete to set, then leveling a screed with its entire under surface supported a considerable distance above the concrete floor, then securing the screed to said screed anchors, then delivering in a continuous manner a stream of plastic material capable of hardening to the floor longitudinally of and adjacent to one side of said screed, and simultaneously applying lateral pressure to the plastic material to force a portion of said plastic material beneath said screed and around said screed anchors.

8. The method of forming a floor support which consists in first providing a plastic concrete floor and inserting therein while in a plastic condition a row of vertically arranged screed anchors, then permitting the concrete floor to harden, then providing a horizontal screed adjacent to said anchors, then temporarily supporting and leveling said screed so that its under surface is entirely above said concrete floor, then rigidly securing said screed to said anchors, then removing the temporary support and delivering in a continuous manner a stream of plastic material capable of hardening to the floor longitudinally of and adjacent to one side of said screed, and simultaneously applying lateral pressure to the plastic material to force a portion of said plastic material beneath said screed and around said screed anchors.

HARRY I. KILLION.
